DESIGN FOR A COMPACT OR SIMILAR ARTICLE

Paul Flato, New York, N. Y., assignor to Paul
Flato Sales Corp., New York, N. Y.

Application January 20, 1948, Serial No. 143,893

Term of patent 14 years

(Cl. D86—10)

To all whom it may concern:

Be it known that I, Paul Flato, a citizen of the United States of America, residing in New York city, county of New York, and State of New York, have invented a new, original, and ornamental Design for a Compact or Similar Article, of which the following is a specification, reference being had to the accompanying drawing, forming part thereof, wherein:

The reverse side of the compact of the side shown in Figure 1 is identical in appearance thereto.

I claim:

The ornamental design for a compact or similar article, substantially as shown and described.

PAUL FLATO.
